LLP

(57) **CLAIM**

I claim the ornamental design for a pet bowl, as shown and described.

DESCRIPTION

FIG. 1 is a top perspective view of an embodiment of a pet bowl showing my new design;

FIG. 2 is a bottom perspective view of the pet bowl of FIG. 1;

FIG. 3 is a top plan view of the pet bowl of FIG. 1;

FIG. 4 is a bottom plan view of the pet bowl of FIG. 1

FIG. 5 is a front elevational view of the pet bowl of FIG. 1;

FIG. 6 is a rear view of the pet bowl of FIG. 1;

FIG. 7 is a right side elevational view of the pet bowl of FIG. 1; and,

FIG. 8 is a left side elevational view of the pet bowl of FIG. 1.

The portions shown in broken lines are included for illustrative purposes only and form no part of the claimed design.

1 Claim, 8 Drawing Sheets
